HAIR CURLER

William Huppert, New York, N. Y., assignor to
Delamere Company, Inc., a corporation of Del-
aware

Application May 26, 1936, Serial No. 81,802

8 Claims. (Cl. 132—44)

This invention relates to a hair curler, and particularly to a curler having a flexible tube around which the hair is wound, a flexible wire member extending over the tube for clamping the ends of the hair thereon, and a flexible wire member extending from each end and adapted to be bent backward to clasp the hair wound on the curler and to hold the curler temporarily in place until the hair has been formed in curl.

10 Among the objects of the invention are to improve and simplify the construction of hair curlers of this type, to provide curlers having few parts that may be inexpensively manufactured and quickly assembled on a high production basis, to provide novel means for attaching the wire members to the tube, as well as to attain other advantages which will appear from the following description of the invention.

In the accompanying drawing, forming a part 20 of this specification:—

Figure 1 is a plan view of the wire members;

Fig. 2 is an enlarged sectional view taken on the line 2—2 of Fig. 1;

Fig. 3 is a side view of the curler showing the 25 wire members assembled to the tube;

Fig. 4 is a longitudinal sectional view on an enlarged scale taken on the line 4—4 of Fig. 3;

Fig. 5 is a view showing the flexible clamping arms bent down to clamp the ends of the hair 30 on the tube;

Fig. 6 is a perspective view of the curler with the hair partly rolled or wound thereon;

Fig. 7 is a perspective view of the curler showing the hair rolled or wound thereon and the 35 flexible clasping wires bent backward; and

Fig. 8 is a longitudinal sectional view of a modified form of the curler.

The curler body consists of a flexible tube 10 made of rubber or other suitable material, and 40 it may be formed with ventilating perforations 11 through its wall.

The wire members may be formed of a single 45 length of flexible wire 12, preferably covered wire, bent to form an arm 13, a second arm 14, and a third arm 15. 16 is a metal clasp plate having an eye 17 and having ears 18 which are rolled or bent around the wire, as shown in Fig. 2, to bind the three arms together. The arms 13, 14 and 15 are each preferably in the form of a loop. In assembling the curler, the wire members are passed through the bore of the tube 10 and the eye 17 of the clasp 16 is brought into registration with a perforation adjacent one end of the tube, as, for instance, the perforation 11a.

55 The wire members are then secured to the tube

by means of a suitable fastener, such as the rivet or eyelet 19 which is passed through the perforation 11a and the eye 17 and is headed at both ends, as best seen in Fig. 4.

It will be noted, on referring to Fig. 1, that the wire is so bent as to provide two arms or loops 13 and 15 extending to one side of the clasp 16 and a single arm or loop 14 to the other side. While I prefer to form all of the arms or loops of a single length of wire, they may be formed 10 of separate pieces bound together by the clasp 16. When the wire members are assembled to the tube, as seen in Fig. 3, the arms or loops 13 and 14 will extend outwardly from the opposite ends of the tube in equal lengths. These arms or 15 loops 13 and 14, when bent backward as shown in Fig. 7, constitute the hair clasping elements of the device. The arm or loop 15 is somewhat longer than the arm or loop 13 and extends outwardly from the same end of the tube as the latter. The arm or loop 15, which constitutes the hair ends clamping element of the device, is of such length that when bent over on the tube, as shown in Fig. 5, it will extend across substantially 20 the entire length of the tube.

In the modification shown in Fig. 8, the tube 10 is provided with a slot 20, adjacent one end of the tube, in addition to the perforations 11. In this form of the device, the arm or loop 15 passes outwardly through a slot 20 in the tube 30 instead of passing around the end of the tube as shown in Fig. 5.

In using the device, the ends of the lock or strand of hair to be curled are placed upon the flexible tube 10 and the flexible clamping arm or 35 loop 15 is bent over and pressed down upon the hair ends whereupon the hair is rolled or wound around the tube. When the desired length of hair has been wound, the two clamping arms or loops 13 and 14 are bent backward over the hair 40 to lock the device temporarily in place.

It is to be understood that I do not limit myself to the precise details of construction herein illustrated and described as various modifications therein may be made within the scope of 45 the invention.

What I claim is:—

1. In a hair curler, a flexible tube, a flexible wire member consisting of a single length of wire bent to form a unitary structure comprising three 50 flexible loops which are bound together by a metal clasp having an extended portion formed with an eye, said wire member being disposed in the bore of the tube and being fastened to the tube, adjacent one end thereof, by means of a 55

- fastener passing through the wall of the tube and the eye of the clasp, one of the flexible wire loops extending lengthwise over the tube, the other two flexible wire loops extending outwardly from 5 the ends of the tube, one from each end.
2. In a hair curler, a flexible tube, a flexible wire member comprising three flexible loops forming a unitary structure bound together by a clasp, said wire member being disposed within 10 the bore of the tube and being fastened to the tube adjacent one end, one of the flexible wire loops projecting outwardly through a slot in the tube, adjacent one end thereof, and extending lengthwise over the tube, the other two flexible 15 wire loops extending outwardly from the ends of the tube, one from each end.
3. In a hair curler, a perforated flexible tube, a flexible wire member comprising three arms forming a unitary structure and bound together 20 by a clasp, said wire members being disposed within the bore of the tube, a fastener passing through the clasp and through one of the perforations of the tube adjacent an end thereof for securing the wire member to the tube, one of the 25 flexible wire arms extending lengthwise over the tube, and the other two flexible wire arms extending outwardly from the ends of the tube, one from each end.
4. In a hair curler, a perforated flexible tube, a 30 flexible wire member comprising three arms bound together by a clasp, said wire members being disposed within the bore of the tube, an eyelet passing through the clasp and through one of the perforations of the tube adjacent an end 35 thereof for securing the wire member to the tube, one of the flexible wire arms extending length-

wise over the tube, and the other two flexible wire arms extending outwardly from the ends of the tube, one from each end.

5. In a hair curler, a perforated flexible tube, a flexible wire member consisting of a single 5 length of covered wire bent to form three loops, a clasp binding the three loops together at a point intermediate the length of said member, said clasp having an eye whereby it is secured to the tube, an eyelet passing through the eye and 10 through the tube, one of the flexible wire loops extending lengthwise over the tube, the other two flexible wire loops extending outwardly from the ends of the tube, one from each end.

6. In a hair curler, a flexible tube, a plurality 15 of flexible wire hair engaging loops held within the bore of the tube and extending outwardly therefrom, and a clasp binding said flexible wire loops together.

7. In a hair curler, a flexible tube, a plurality 20 of flexible wire hair engaging arms disposed within the bore of the tube and extending outwardly therefrom, and a clasp binding said flexible wire arms together, said clasp being fastened to the tube.

8. A hair curler comprising a rubber tube and three wire engaging arms consisting of a single 25 length of flexible covered wire bent to form three loops which are bound together by a clasp, one of the flexible wire loops being bent to extend 30 lengthwise over the tube, the other two wire loops extending outwardly from the ends of the tube, one from each end, and being adapted to be bent over hair wound on the tube.
